UNITED STATES PATENT OFFICE.

WILLIAM N. BEST, OF BROOKLYN, NEW YORK, ASSIGNOR TO W. N. BEST, INC., OF NEW YORK, N. Y., A CORPORATION OF NEW YORK.

LIQUID-FUEL-BURNING APPARATUS.

1,407,511.

Specification of Letters Patent. Patented Feb. 21, 1922.

Application filed December 27, 1919. Serial No. 347,774.

To all whom it may concern:

Be it known that I, WILLIAM N. BEST, a citizen of the United States, and a resident of Brooklyn, in the county of Kings and State of New York, have invented certain new and useful Improvements in Liquid-Fuel-Burning Apparatus, of which the following is a specification.

This invention relates to liquid fuel burning systems and more particularly to those systems in which the liquid or semi-plastic fuel is sprayed or atomized by the expansion of a fluid under high pressure escaping across the fuel outlet. In order to obtain proper combustion, it is essential that the quantity of liquid fuel delivered should not be in excess of that which can properly burn with the available air supply. If a larger quantity of fuel be delivered, no increased heating effect is secured and smoke will be produced. In many places in which the burner is used, the person in charge cannot ascertain whether or not smoke is being produced without traveling to some little distance from the burner in order to see the top of the stack. As a result I have found that there is a tendency on the part of the operator to produce a smoky flame, contrary to the ordinances of many cities, when he endeavors to get the maximum heating effect.

The main object of my invention is to provide means whereby the flow of fuel to the burner may be regulated and controlled and the regulation maintained free from tampering or readjustment by the operator.

In carrying out my invention I provide, at some point in the liquid fuel supply line, couplings including a threaded nipple screwed into one of the coupling members and having an aperture which will prevent the passage of liquid fuel at a greater rate than said fuel can be properly and completely burned without smoke in the combustion chamber. This perforated and threaded nipple is of such construction that when the coupling members are separated, it may be readily removed, or replaced by one having a larger or smaller passage. The thimble or nipple is so designed and secured that it cannot fall out or become accidentally displaced when the coupling members are separated. It cannot be operated or manipulated from the exterior or while liquid under pressure is passing through the line. The coupling is preferably of such construction

that it may be locked and the operator thus prevented from gaining access to the nipple or thimble for purposes of exchange or enlargement of the aperture.

In the accompanying drawings I have illustrated one embodiment of my invention, although it will be evident that others may be readily designed within the spirit of my invention and without departing from the scope thereof as defined in the appended claims.

In these drawings:

Figure 1 is a side elevation of a portion of a liquid fuel burning outfit incorporating my improved construction and showing the burner in vertical section;

Figure 2 is a central longitudinal section through the improved regulating or controlling device, said section being taken on the line 2—2 of Figure 3;

Figure 3 is a side elevation at right angles to the plane of Figure 2;

Figure 4 is an end view;

Figure 5 is an end view of the nipple or thimble;

Figure 6 is a central longitudinal section on the line 6—6 of Figure 5; and

Figure 7 is a view similar to Figure 6, but showing a nipple having a larger passage.

I have illustrated my improved construction in connection with a burner similar in details of construction and operation with that shown in the patent of Annie H. Best, No. 1,351,550, issued August 31st, 1920. In this construction the burner head has two pipes 10 and 11 connected thereto, one of these, 10, is for steam or compressed air and the other, 11, for liquid or semi-plastic fuel, such as fuel oil, crude oil, tar or the like. The burner head has a fuel passage 12 terminating in an upwardly facing outlet 13 and has an expansive fluid passage 14 terminating in an outlet 15 delivering substantially at right angles across the fuel outlet 13. The burner head has a nozzle piece 16 defining the upper side of the expansive fluid outlet 13, this nozzle piece being held in place by a bolt 17 or other suitable means. I do not wish to be in any way limited to this specific construction, or even to this type of construction, as my invention is applicable to any system in which the liquid fuel is delivered to a burner or nozzle and there atomized by the expansion or flow of a fluid.

At some point in the liquid fuel supply line between the source of supply and the burner, I provide my improved regulating means. This may be closely adjacent to the 5 burner and beyond the usual regulating cock and shut-off valve, or it may be farther back in the line in the rear of these usual parts.

In the specific form illustrated there are 10 provided two coupling members 18 and 19 having abutting ends and means for rigidly securing these abutting ends together. The securing means is shown as a collar 20 threaded on to a neck or extension of the members 19 and having an inwardly extending 15 flange engaging with the opposite side of a seat or shoulder 22 on the member 18. One of these members, for instance, the member 18 has an enlarged threaded socket or aperture in its end adapted to receive the 20 externally threaded nipple or thimble 23. This is shown as having a peripheral collar or flange 24 limiting the extent to which it can be screwed into the socket and having flanges or butterfly-nut extensions 25 which 25 facilitate the insertion or removal of the nipple. The outer end of the nipple is preferably convex and through the end wall is a passage 26, the size of which is accurately determined in accordance with the character 30 of fuel employed, the pressure under which it is delivered, the size and character of the burner and the character of the combustion chamber, particularly regarding the available air supply of the latter. The passage 35 26 is preferably somewhat conical, the outer end which receives the liquid being of smaller diameter.

The member 19 has a chamber or socket 27 in its end which receives the projecting 40 end portion of the thimble, as shown particularly in Figure 2. The separation of the two members of the coupling by the unscrewing of the member 20 leaves the thimble rigidly and firmly secured to the 45 member 18, but projecting from the end surface of the latter so that the thimble may be unscrewed by fingers or with a wrench, screw driver or other tool. It is important that upon the separation of the 50 coupling members, the thimble shall not be free to fall out or become accidentally detached from the part carrying it. I may provide a series of these thimbles or nipples with different size passages therethrough so 55 that after proper examination or experimentation a thimble having the proper size of passage may be inserted and the flow of too much liquid to the burner thus prevented. In Figure 6, I have shown one 60 thimble and in Figure 7 a second thimble with a larger passage 26a.

In order to prevent the operator from 65 removing the thimble, or enlarging the passage, or gaining access to the thimble for purposes of removing or tampering with the

latter, I preferably provide means whereby the coupling members may be locked together. As an example of means for locking the parts, I have shown the collar 20 with a tooth or serrated flange 28. The 70 coupling member 19 is shown as having a pair of lugs 29 and a key 30 of such form that it may lie between the two lugs and engage between two of the adjacent teeth, or in a notch or recess of the flange 28 to 75 prevent rotation of the collar 20 when the key is in place. To prevent removal of the key any suitable locking means may be employed. I have shown a padlock 31 having the bolt or other secured part thereof passing 80 registering apertures in the lugs 29 and engaging with an outer side of a key 30. A key of the form shown cannot be moved endwise in either direction to release the collar 20 until after the padlock 31 has been 85 removed.

By means of my improved construction the system may be set so that more than the predetermined amount of fuel cannot be delivered to the burner although only a 90 smaller amount may flow as a result of partially closing the ordinary regulating valve. With the valve wide open the operator cannot deliver such a quantity of liquid fuel to the burner as will result in 95 the production of smoke. If the device be used in connection with heating or power plants in municipalities having anti-smoke ordinances, the owner may practically insure himself against liability of violation of 100 the law through carelessness or ignorance on the part of the employees supervising the production of the heat.

Having thus described my invention what I claim as new and desire to secure by Letters Patent is:

1. The combination with a liquid fuel burner having a liquid fuel outlet and an expansive fluid outlet delivering thereacross to spray the liquid fuel into the combustion chamber, of means for controlling the delivery of liquid to its outlet including a pair of separable coupling members in the supply conduit to said liquid fuel outlet and independent of the supply conduit to said expansive fluid outlet, and a thimble secured in one of said coupling members but unattached to the other, and having a passage therethrough of predetermined cross-sectional area, materially 115 smaller than the liquid fuel outlet of the burner.

2. The combination with a liquid fuel burner having a liquid fuel outlet and an expansive fluid outlet delivering thereacross to spray the liquid fuel into the combustion chamber, of a regulator in the liquid fuel supply conduit leading to said liquid fuel outlet and including a pair of coupling members detachably secured together, and 120

- a thimble detachably threaded into the end of one of said members and carried solely by said member, and having a fuel regulating passage therethrough materially smaller than the liquid fuel outlet from the burner. 3. The combination with a liquid fuel burner having a liquid fuel outlet and an expansive fluid outlet delivering there-across to spray the liquid fuel into the combustion chamber, of a fuel regulator in the conduit delivering to said liquid fuel outlet and including a pair of coupling members having directly abutting ends, a collar for detachably securing said members together and a third member carried by but detachable from one of said coupling members and projecting into but unattached to the other coupling member and having a fuel regulating passage therethrough materially smaller than the liquid fuel outlet of the burner.
4. A liquid fuel regulator including a pair of coupling members, one of said members having a recess in the end thereof and a pair of lugs on the side thereof and the other of said members having a threaded socket in the end, a nipple having a fuel regulating passage therethrough and detachably secured within said threaded socket and projecting axially into said recess, a collar engaging with said second mentioned member and threaded on to said first mentioned member and having a serrated peripheral flange, a key disposed between said lugs and engaging with said flange, and locking means for retaining said key in position.

Signed at New York, in the county of New York and State of New York, this 26th day of December A. D. 1919.

WILLIAM N. BEST.
